UNITED STATES PATENT OFFICE.

EDWIN F. WILLIAMS, OF CHICAGO, ILLINOIS.

STEAM-ENGINE GOVERNOR.

SPECIFICATION forming part of Letters Patent No. 408,153, dated July 30, 1889.

Application filed October 5, 1888. Serial No. 287,324. (No model.)

To all whom it may concern:

Be it known that I, EDWIN F. WILLIAMS, a citizen of the United States, residing at Chicago, in the county of Cook and State of Illinois, have invented a certain new and useful Improvement in Steam-Engine Governors, which is fully set forth in the following specification, reference being had to the accompanying drawings, in which—

10 Figure 1 represents an elevation of a construction embodying my invention; Fig. 2, a sectional view of the same, taken on the line 1 1 of Fig. 1; Fig. 3, a view similar to Fig. 1, showing my invention in a modified form; Fig. 15 4, a plan view of the construction shown in Fig. 3, the rear portion thereof being in section upon the line 2 2 of said figure; and Fig. 5, a diagram illustrating the operation of the device.

20 Like letters refer to like parts in all the figures of the drawings.

My invention relates to that class of steam-engine governors in which the regulation is automatically effected by changing the position of an eccentric on the shaft, so as to give a greater or less degree of eccentricity, properly conditioned to give a longer or shorter period of opening to admit steam to the cylinder at each stroke.

30 My invention is applicable both to that class of engines wherein a single valve operating upon a fixed seat is employed in connection with an eccentric of variable positions, and also to that class wherein a main 35 valve operated by a fixed eccentric is employed in conjunction with a cut-off valve moving upon or in said main valve and controlled by a second eccentric variable in its position with relation to the shaft.

40 The object of my present invention is to provide a simple and effective governing mechanism which shall be free from complication of parts, well balanced in the arrangement of parts, and free from friction.

45 To these ends my invention consists in certain novel features, which I will now proceed to describe, and will then particularly point out in the claims.

In the drawings, A represents the main shaft 50 of the engine, and B a pulley or wheel keyed or otherwise secured thereon. This pulley or

wheel may or may not be employed as a driving-pulley, as desired.

C represents the shifting or variable eccentric, which is provided with a slot c, through which the shaft A passes, which slot permits the eccentric to move across the shaft in the manner hereinafter described.

C' represents an arm which supports the eccentric C, one end of said arm being pivoted to the pulley B, as shown at c', by means of a suitable pivot-bolt, its other end being formed in one piece with or secured to the hub C² of the eccentric C. At about ninety degrees from the arm C' a second arm c² extends outward 65 from the hub C².

D represents a governor-arm pivoted to the pulley B at d, and provided near its free end with an adjustable weight D'. The free end of the arm D is connected to the arm c² by 70 means of a spring E. The spring E is what is known as a "strap" or "flat" spring, and its ends are secured to the arms D and c² by means of screw-bolts e or other suitable means. It has preferably a normal curvature, substantially such as is shown in the drawings.

F represents a coiled spring, one end of which is suitably connected to the arm c², its other end being connected to the rim of the 80 pulley B by means of an adjusting-screw f, which serves to regulate the tension of said spring.

As before stated, I have shown in Figs. 1 and 2 of the drawings, a governor wherein the 85 construction just described is adapted for use in connection with a single-valve engine, wherein the slide-valve works upon a fixed seat and the regulation of the steam is effected by the distance traveled by said valve. When 90 the eccentric C is in the position shown in Figs. 1 and 2, the valve operates to admit the maximum amount of steam to the cylinder, this maximum being of course determined by the relative proportions of the valve and valve-seat and their ports. When the eccentric is moved over to the other extreme, the travel of the valve is reduced to a minimum and is about equal to the lap, so that practically no steam is admitted to the cylinder. The various intermediate positions of the eccentric 95 between these two extremes give various in-

termediate amounts of steam to the cylinder, the point of cut-off changing with each change in the position of the eccentric. Let it be supposed, for instance, that the engine is running at normal speed with a load sufficient to maintain the parts in the position shown. Upon any diminution in this load the speed of the engine will increase proportionately, and this increased speed will cause the weighted governor-arm D to move outward to a corresponding extent. This outward motion of the governor is against the centripetal force of the spring E, which spring serves as a link to transmit the motion of the arm D to the eccentric C. The eccentric C then moves inward, or, in other words, its center approaches the center of the shaft A, thereby diminishing its eccentricity. This movement takes place around the pivot c' as a center. The decrease of the eccentricity correspondingly diminishes the travel of the valve, and consequently reduces the rate of speed until it again becomes normal. Conversely, upon any increase in the load the speed diminishes and the centripetal action of the spring E overcomes the diminished centrifugal force of the governor-arm D, and the eccentric C is moved outward to a corresponding extent, thus increasing the travel of the valve and bringing the speed of the engine up until it becomes normal. It will thus be seen that the governor-arm D provides a centrifugal force and the spring E a centripetal force, which act in opposition to each other, and which upon any change in the rate of speed of the engine so move the eccentric as to render the speed normal. The spring F, although supplying a portion of the centripetal force, is employed chiefly for the purpose of providing a ready means for adjusting said force and is supplemental to the spring E. The difficulties attendant upon the adjustment of the force of a flat spring, such as E, will be at once apparent, and for this reason I employ the spring F, of adjustable tension, for increasing or diminishing the centripetal force without necessitating any interference with the spring E. It will also be observed that the spring E, while acting as a link to connect the governor-arm and eccentric, possesses various advantages over such a link, since all pivot-joints, with their attendant friction and liability to wear loose, are done away with by the employment of said spring. Moreover, the arrangement of parts is such that the several elements balance each other and reduce the friction at the various pivots to a minimum. The weighted governor-arm D also tends to hold the eccentric firmly in position and prevent any vibrations thereof.

In Figs. 3 and 4 of the drawings I have shown a construction in which my improved governor is applied to that class of engines in which a cut-off valve separate and distinct from the main valve and moving thereon or therein is employed. In this construction the elements are substantially the same as those

just described, the eccentric C becoming the cut-off eccentric. C^3 represents the eccentric-strap, and c^3 the eccentric-rod, which leads to a rocker-arm, from which the cut-off valve is operated. G represents the main eccentric, which is fixed upon the shaft A, and is provided with a strap G' and rod g , by means of which the main valve is operated. It will be observed that the eccentricity of the two eccentrics is opposite, this being the case because I have shown a construction adapted for use in connection with an intermediate rocker-arm for operating the cut-off valve, which rocker-arm reverses the direction of motion of said valve with respect to its eccentric. If this rocker-arm be omitted, the eccentrics will of course be arranged on the same side of the shaft A. In this construction the main eccentric is fixed upon the shaft A, and consequently its center is at a fixed distance from its axis of rotation, so that the main valve has a fixed travel. The governor regulates the position of the cut-off eccentric in the manner hereinbefore described, and the effect of the changes in the position of the cut-off eccentric is to cause an earlier or later cut-off, according to the relative positions of the centers of the main and cut-off eccentrics. The throw, however, of the cut-off eccentric is practically constant, and the throw of the cut-off valve within or upon the main valve is practically unchanged in extent, however its period of motion may be changed by the changes in the position of its actuating-eccentric. For a clearer explanation of this reference is to be had to the diagram shown in Fig. 5. To avoid complications in the description, the said diagram has reference to a construction in which both the main and cut-off eccentrics have their eccentricity on the same side of the shaft A, or, in other words, to a construction in which no rocker-arm for the cut-off valve is employed. It will be of course understood that what applies to this construction applies equally well to a construction where the eccentrics are opposite.

Let a represent the center or axis of rotation of the main shaft, z the crank-pin center, and q the center of the main or fixed eccentric. Let it be supposed that the cut-off eccentric be revolved around the center q of the main eccentric, so that its center will describe the circle $s s' s^2$. It is obvious that in this case the throw of the cut-off valve within or upon the main valve will be unchanged in extent, but will occur earlier or later with respect to the motion of the main valve, according to the position occupied within the circle $s s' s^2$. Assuming that a movement through the arc $s s' s^2$ would cause a variation in the point of cut-off of ninety degrees from the beginning of piston-stroke, when the center of the cut-off eccentric is situated at the point s' the cut-off would occur at half-stroke, and when at s^2 at 0 or beginning of stroke. The same result may be very closely approximated by moving the center of the cut-off ec-

centric through the arc $s s' s^2$, described from the point p as a center, instead of from the point q . The variation in the throw in this latter case is so slight that it practically amounts to nothing. The point p corresponds, of course, to the pivot c' of the arm C' . In either case the motion of the cut-off eccentric is around a point outside of the axis of revolution of the main shaft. The diagram in Fig. 5 also shows the movement heretofore employed in single-valve shifting-eccentric engines. In this construction, q is supposed to represent the center of the shifting eccentric, and p' the point around which it has its governing motion. When the center is at q , the eccentric has its maximum throw, and when the center is at q' its minimum throw. It will be observed that in this case the movement of the eccentric center is practically perpendicular to the radius of the shaft A , while in the movement employed by me the motion of the eccentric center is practically radial to the said shaft. However, when the construction shown in Figs. 1 and 2 is employed this old movement may be used, although I prefer the one previously described.

It is obvious that various modifications in the details of construction and arrangement of parts may be made without departing from the principle of my invention, and I therefore do not wish to be understood as limiting myself strictly to the precise details hereinbefore described, and shown in the drawings.

Having thus described my invention, what I claim as new, and desire to secure by Letters Patent, is—

1. In a steam-engine governor, the combination, with the shaft and wheel fixed thereon, of a shifting eccentric on the shaft, a weighted governor-arm secured to the wheel, and a strap-spring connecting the governor-arm to the eccentric, substantially as and for the purposes specified.

2. In a steam-engine governor, the combination, with the shaft and wheel, of the slotted eccentric and its supporting-arm pivoted to said wheel, the weighted governor-arm pivoted to the wheel, and a strap-spring connecting the governor-arm and eccentric, said governor-arm furnishing the centrifugal force and said spring furnishing the centripetal force, substantially as and for the purposes specified.

3. In a steam-engine governor, the combination, with the shaft and wheel, of the slotted eccentric and its supporting-arm, the governor-arm connected to said eccentric by a centripetally-acting flat spring, and a spiral spring of adjustable tension connecting the eccentric and wheel and supplementing the centripetal action of the flat spring, substantially as and for the purposes specified.

4. In a steam-engine governor, the combination, with the shaft A and wheel B fixed thereon, of the eccentric C , slotted at c and provided with hub C^2 , having arm C' , pivoted to the wheel at c' , and arm c^2 , the weighted governor-arm D , the spring E , connecting said governor-arm and the arm c^2 , and the coiled spring F , connected to the arm c^2 at one end and adjustably connected to the wheel by a bolt f at the other end, substantially as and for the purposes specified.

5. In a steam-engine governor, the combination, with the main eccentric fixed on the shaft, of the cut-off eccentric capable of movement across the shaft and having its center of motion at a point outside of the axis of the shaft, said cut-off eccentric being so arranged that the path of motion of its center is substantially radial to the shaft, substantially as and for the purposes specified.
